UNITED STATES PATENT OFFICE.

EDWARD R. C. MORGAN, OF MUMBLES, SOUTH WALES, ENGLAND, ASSIGNOR
TO ABRAHAM MORREL, OF NEW YORK, N. Y.

IMPROVED ANCHOR.

Specification forming part of Letters Patent No. 43,273, dated June 21, 1864.

To all whom it may concern:

Be it known that I, EDWARD R. C. MORGAN, of the village of Mumbles, in the county of Glamorgan, South Wales, England, have invented a new and Improved Anchor; and I do hereby declare that the following is a full and exact description thereof, reference being had to the accompanying drawings, and to the letters of reference marked thereon.

The nature of my invention consists in the arrangement of the two flukes hinged to the anchor shank by separate bolts, independent of each other and connecting the two flukes together by means of a segment passing through a suitable hole or slot in the shank, whereby, while the lower fluke will, by its own weight, fall into the desired position, the upper fluke will be moved near to the shank to prevent any fouling of the cable, and at the same time prevent any strain on the upper fluke or shank.

By this improvement the cable is also prevented from fouling the anchor, and in case of one fluke breaking the anchor will easily reverse and hold with the second fluke.

In the accompanying drawings, Figure I represents a front view of my improved anchor. Fig. II shows a side view of the anchor-shank, and Fig. III a side view of the fluke.

Similar letters represent similar parts.

A is the stock of the anchor; B, the shank. The lower end or crown of the shank, C, is furnished with two projections or catches, D D.

E E are the two flukes, fixed independent of each other to the crown C of the anchor-shank by means of the two bolts n n. The flukes E E are connected together by a curved arm, G, passing through a hole or slot, h, in the throat of the anchor-shank. On each side of the throat projections m m are made, fitting partly around the hub of the flukes.

When the lower fluke takes hold of the bottom, the curved arm G holds the upper fluke onto the shank, but at the same time the lower fluke comes against the projection D on the crown C, while the upper end of the hub of said fluke bears against the projection m on the throat of the shank, in consequence of which the whole strain on said fluke is taken by this projection D on the crown, in combination with the projection m on the throat. The projection D is so arranged and the curved bar G is made of such a length that while the upper fluke is brought onto the shank by the lower fluke through the curved arm G no pressure or strain is brought on the same.

The great advantages of my improved anchor consist in its increased efficiency with reduced weight, affording material relief to ships' bows in a head sea, facility of transportation to and from ships, and convenience of stowage, as the same is composed of several parts which can be readily taken to pieces, and with facility put together again. Besides, the flukes being separate and independent, the same can be more easily forged and give the opportunity of having one spare fluke in case of accident, or if one fluke should break away on weighing the anchor.

What I claim as my invention, and desire to secure by Letters Patent, is—

Connecting the two flukes of an anchor, hinged to the shank by separate bolts, by a curved bar, G, passing through a suitable hole, h, in the shank, in the manner and for the purpose substantially as described and set forth.

EDWARD R. C. MORGAN.
